Primary Examiner — George D. Kirschbaum*Assistant Examiner* — Joseph K Kukella(74) *Attorney, Agent, or Firm* — Morris, Manning & Martin, LLP; Adam J. Thompson(57) **CLAIM**

The ornamental design for the RFID reader for gaming table, as shown and described.

DESCRIPTION

FIG. 1 is a top perspective view of an RFID reader for gaming table.

FIG. 2 is another top perspective view thereof.

FIG. 3 is a front view thereof.

FIG. 4 is a rear view thereof.

FIG. 5 is a side view thereof.

FIG. 6 is a side view thereof, from the side opposite that of FIG. 5.

FIG. 7 is a top plan view thereof.

FIG. 8 is a bottom plan view thereof; and,

FIG. 9 is a perspective view of the RFID reader for gaming table in a gaming table.

The broken lines depicted in FIGS. 1-18 are for the purpose of illustrating environmental structure and form no part of the claimed design.

1 Claim, 9 Drawing Sheets(56)
